A. B. SINCLAIR,
SPRING COILING MACHINE,
APPLICATION FILED APR. 9, 1920.

1,407,891.

Patented Feb. 28, 1922.

UNITED STATES PATENT OFFICE.

ALEXANDER B. SINCLAIR, OF SOUTH HADLEY FALLS, MASSACHUSETTS, ASSIGNOR TO SLEEPER & HARTLEY, INC., OF WORCESTER, MASSACHUSETTS, A CORPORATION OF MASSACHUSETTS.

SPRING-COILING MACHINE.

1,407,891.

Specification of Letters Patent. Patented Feb. 28, 1922.

Application filed April 9, 1920. Serial No. 372,599.

To all whom it may concern:

Be it known that I, ALEXANDER B. SINCLAIR, a citizen of the United States, residing at South Hadley Falls, in the county 5 of Hampshire and Commonwealth of Massachusetts, have invented a new and useful Improvement in a Spring-Coiling Machine, of which the following, together with the accompanying drawings, is a specification.

10 My invention relates to spring coiling machines and has for its object to provide certain improvements in the spring coiling machine shown and described in United States Letters Patent No. 1,266,070, issued May 14, 15 1918, to Frank H. Sleeper.

The above mentioned patent shows and describes a machine for coiling or forming wire springs by causing the wire to be coiled around an arbor. The said machine comprises instrumentalities for controlling the feed of the wire, for varying the form of the spring coiled and for severing the completed coils. The operations of the several instrumentalities are simultaneously controlled from a drive shaft through cam devices, whereby the wire is fed, coiled and a completed coil cut off for each complete revolution of the cam shaft. In the patented machine, springs formed from only one predetermined length of wire can be produced for a given setting of the machine, it being necessary to make certain rearrangements of gearing and other mechanism in order to vary the length of wire that will be coiled for 25 each revolution of the cam shaft.

By my invention, I propose to improve the above described machine, by providing a novel form of timing device to be used in connection with the coil severing devices, 40 whereby the completed coil may be cut off after more than one revolution of the cam shaft. In this way coils containing different lengths of wire may be produced with but a slight adjustment of my timing device and 45 without disturbing the previous setting of the other parts of the machine.

In the accompanying drawings,

Fig. 1 is a view in front elevation of a coiling machine embodying my invention.

50 Fig. 2 is a rear elevation in partial section of the machine shown in Fig. 1.

Fig. 3 is an enlarged detailed view of the coiling arbor employed in the machine.

55 Figs. 4, 5 and 6 are fragmentary views in side elevation showing the various positions

occupied by the parts of my improved timing device.

Fig. 7 is an enlarged detail view of the parts of the timing device.

Fig. 8 is a transverse sectional view of the 60 timing device.

Like reference characters refer to like parts in the different figures.

Referring to Fig. 1 of the drawings, the machine generally comprises upright sides 65 or housings 1 and 2 mounted upon a suitable base 3, the various spring forming tools and their associated operating members being mounted upon and between the housings 1 and 2. The horizontal line of the wire feed 70 is indicated by the arrow at 4, the wire being fed through a preliminary guide 5 mounted on the housing 1.

A plurality of pairs of feed rolls 6, 6 and 7, 7 are adapted to grip the wire as it 75 emerges from the guide 5 and to feed it forward to the coiling tools. Grooved guides 8 are provided between the feed rolls and similarly grooved guides 9 are provided to receive the wire from the rolls 7, 7. The two 80 pairs of feed rolls 6 and 7 are geared together for synchronous rotation and means are provided for driving the rolls intermittently in a manner fully set forth and described in the above mentioned Patent No. 85 1,266,070.

As the wire is fed through the guide 9 by the feed rolls, it passes over, or under, an arbor 10 and against a coiling point 11, the point deflecting the wire downward or upward according to the adjustment of the coiling tools, to produce either a right hand or a left hand spring. The arbor 10 is mounted in a tool holder 12 which is provided with an opening extending therethrough, so that the arbor 10 may be inserted from either end of the tool holder 12. As best shown in Fig. 3, the arbor 10 is provided at each end with a tip 13 substantially semi-circular in cross section, the tip at one end 100 being adapted for the formation of a right hand coil and that on the opposite end for the formation of a left hand coil. The tip 13 is provided with a cutting edge 14 for co-operation with a cutting tool in severing the 105 wire, as hereinafter described. The tip 13 is supported below the line of feed for the formation of a right hand coil as shown in Fig. 1, and it is obvious that it may be positioned above the line of feed for the forma- 110

- tion of a left hand coil by reversing the tool holder 12. The coiling point 11 is adjustably mounted in a slide 15 that is adapted to be reciprocated to and fro approximately 5 in the center of the line of wire feed by means of a crank arm 16. The arm 16 is adapted to be oscillated through suitable instrumentalities, fully shown and described in the above mentioned Patent No. 1,266,070.
- 10 It is obvious that the diameter of the coil formed upon the arbor 10 will be determined by the relative position of the coiling point 11 with respect thereto.
- After a coil has been formed on the arbor 15 in the manner described above, it is adapted to be severed by either one of two cutting tools 17 and 18. The cutting tools 17 and 18 consist preferably of rectangular bars of steel suitably mounted by means of clamps 20 19 and 20 upon pivotally mounted heads 21 and 22. The tool 17 is adapted to cooperate with the cutting edge 14 of the arbor 10 when the latter is in position to form a right hand coil, as shown in Fig. 1, and the 25 tool 18 is similarly adapted to cooperate with the arbor 10 when the latter is in position to form a left hand coil. The cutter heads 21 and 22 are respectively mounted upon shafts 23 and 24 extending between 30 the housings 1 and 2. As best shown in Fig. 2, the shafts 23 and 24 project beyond the end of the housing 2 and are provided with end clamps 25 and 26 connected by a link 27, whereby the heads are adapted to be 35 moved in unison.
- The shaft 23 is provided with a rocker arm 28 that is connected to a pivotally mounted cam lever 29 by means of a link 30. The cam lever 29 is adapted to be actuated by a cam 31 mounted on a cam shaft 32. The cam shaft 32 is driven from a suitable source of power, not shown, which also 40 has additional devices cooperating therewith for controlling the operation of the feed rolls 6 and 7 and of the other coiling tools. All of the parts described thus far are shown in the above mentioned Patent No. 1,266,070, and further description of the other instrumentalities referred to, but not 45 shown, is omitted for the sake of brevity.
- The cam lever 29 is provided at its end with a stud 33 upon which is mounted my novel form of timing device, which will now be described. As best shown in Figs. 7 and 50 8, the timing device comprises a cam 34 and a timing disk 35 mounted side by side upon a shoulder 36 of the stud 33 and secured together by a pin 37. The working face 38 of the cam 34 subtends an angle of ninety 55 degrees, and the disk 35 is similarly provided with a face 39. The disk 35 is also provided with points 40 and 41 that are spaced ninety degrees apart from each other and from the extremities of the face 39. The cam 34 and disk 35 are secured together, 65 with the faces 38 and 39 registering with each other, as shown in Fig. 2. While the cam and disk are loosely mounted on the stud 33, they are frictionally held in any position by a spring pressed plunger 42 in 70 the head of the stud 33. The shaft 32 also carries a post 43 diametrically opposite to the cam 31 and movable therewith. The cam 31 is adapted to engage the face 38 of the cam 34 and the post 43, being offset 75 from the cam 31, is adapted to engage the points 40 and 41 of the disk 35. A stop arm 44 may be adjusted in order to regulate gages the end of the cam lever 29 to hold it against the action of a spring 46 when 80 the cam 31 is free from the cam 34, as will hereinafter appear. The position of the arm 44 may be adjusted in order to regulate the upward travel of the cam lever 29.
- Having thus described the various parts 85 entering into my invention, the operation thereof is as follows:—The wire is fed forward by the rolls 6 and 7 and is deflected around the arbor 10 by the coiling point 11, as previously described, the operation of the 90 feeding rolls and coiling tools being so controlled from the cam shaft 32 that a predetermined length of wire is coiled for each revolution of the cam shaft. In the previously described machine, the cam 31 is 95 adapted to move the cam lever 29 downward for each revolution of the cam shaft 32, thereby causing the actuation of the cutter heads 21 and 22 for severing the completed spring. With my improved timing device 100 applied to the machine, however, it is possible to allow the feeding and tool controlling devices to be operative through more than one revolution of the cam shaft 32, before bringing the severing devices into operation, as will now be described.
- Referring to Fig. 2, the cam 34 is in such position that it is just about to be engaged by the cam 31, so that the rotation of the cam shaft 32 will cause the cam lever 29 to 105 be moved downward, as shown in dotted lines, and so operate the cutting heads to sever either a right or left hand coil. It is obvious that during the movement of the lever 29 about its pivot, the cam 31 will turn 110 the cam 34 upon the stud 33 through substantially ninety degrees and will leave the disk 35 in such a position that the post 43 will engage the end of the face 39 upon the next half turn of the cam shaft and so move 115 it into the position shown in Fig. 4. The cam 34 is then out of the path of movement of the cam 31, so that the cam lever 29 will not be moved upon the completion of the first revolution by the cam shaft 32. The 120 post 43 will engage the point 40 upon the completion of the next half revolution of the cam shaft and turn the disk 35, as shown 125

in Fig. 5. It is obvious that the cam 31 may then complete its second revolution without engagement with the cam 34, and that the post 43 will again turn the disk 35 when it 5 engages the point 41, as shown in Fig. 6. This last movement of the disk 35 again brings the cam 34 into the position shown in Fig. 2, so that it will be engaged by the cam 31 as the cam shaft 32 completes its 10 third revolution. In this way a spring will be formed upon the arbor 10 that contains three times as much wire as a spring formed in the previously described machine.

It is obvious that if it is desired to form 15 a spring for every two complete revolutions of the cam shaft, it is only necessary to place another post diametrically opposite the post 43, in which case the points 40 and 41 will be engaged for each half turn of the cam 20 shaft. Obviously, the length of wire in any of the springs can be varied within a wide range by increasing or decreasing the number of posts on the cam shaft 32 and the 25 number of points on the timing disk 35, and also by varying the angular relation between the timing points and the posts. My timing device can be readily applied to any of the previously constructed machines of 30 this type by merely substituting it for the cam or roller formerly provided on the lever 29. Various forms of timing disks can be utilized to produce springs containing different lengths of wire without disturbing in any way whatsoever the adjustment of the 35 machine, as a whole. In this way, springs of almost any desired length can be formed in one machine.

While I have shown my invention as applied to a particular type of machine, it 40 is not so limited but is susceptible of various modifications within the scope of the appended claims.

I claim,

1. In a spring coiling machine, the combination with wire feeding devices, coiling tools, a wire severing device cooperating therewith, and a rotating shaft for controlling the coiling tools, of a cam device for actuating said severing device from said 45 shaft, and a timing device operated by the rotation of said shaft and co-operating with said cam device to cause actuation of the severing device only after the completion 50

of more than one revolution by the said shaft. 55

2. In a spring coiling machine, the combination with wire feeding devices, coiling tools, a wire severing device cooperating therewith, and a rotating cam shaft controlling the coiling tools, of a lever operated 60 by a cam carried on said shaft for actuating the severing device, and means depending upon the rotation of same cam shaft for rendering the cam inoperative until after the shaft shall have turned through more 65 than one complete revolution.

3. In a spring coiling machine, the combination with wire feeding devices, coiling tools, a wire severing device cooperating therewith, and a rotating cam shaft for controlling the coiling tools, of a lever operatively connected to the severing device and provided with a cam acted upon by a cam carried on said shaft, and means for turning one of the cams out of the path of movement of the other until after the shaft shall have turned through more than one complete revolution. 70

4. In a spring coiling machine, the combination with wire feeding devices, coiling tools, a wire severing device cooperating therewith, and a rotating cam shaft for controlling the coiling tools, of a lever operatively connected to the severing device and provided with a cam acted upon by a cam 80 carried on said shaft, the said cams having projecting portions moving therewith and adapted to engage each other and render the cams inoperative until after the shaft shall have turned through more than one complete revolution. 90

5. In a spring coiling machine, a wire feeding mechanism, a coiling arbor provided with a cutting edge, means for maintaining said arbor with its cutting edge either above 95 or below the line of wire feed, a pair of swinging cutter heads, one above and one below said arbor, means for simultaneously swinging said cutter heads toward the arbor, a cam shaft controlling the formation of 100 a coil on said arbor, and means for operating the cutter heads only after the cam shaft has made more than one revolution.

Dated this first day of April, 1920.

ALEXANDER B. SINCLAIR.
